UNITED STATES PATENT OFFICE.

OVERTON M. BENNETT, OF UNIONDALE, PENNSYLVANIA.

CHICKEN FEEDER.

1,417,226.

Specification of Letters Patent. Patented May 23, 1922.

Application filed May 9, 1921. Serial No. 467,953.

To all whom it may concern:

Be it known that I, OVERTON M. BENNETT, a citizen of the United States, residing at Uniondale, in the county of Susquehanna and State of Pennsylvania, have invented certain new and useful Improvements in Chicken Feeders, of which the following is a specification, reference being had to the accompanying drawings.

10 This invention relates to animal feeding devices, and particularly to chicken feeders.

The general object of the invention is the provision of a feeder of this character designed to contain ordinary feed, water and 15 grit, the feeder being so constructed as to provide means for preventing the little chickens from spilling their feed or contaminating it.

A further object is to provide a device of 20 this character wherein the feed, water and grit is contained within a pan low enough to permit chickens to feed therefrom, this pan being protected on all four sides by a guard formed of transversely extending 25 strips of metal and supported by corner posts of angular metal, the lowermost strip being adjustable so as to control the distance between it and the upper edge of the pan to thus prevent chickens from entering 30 the space between the lowermost strip and the edge of the pan and getting into the feed trough and preventing larger chickens or full grown chickens from inserting their heads into the feeder.

35 And a further object is to provide a device of this character with a roof formed in two parts and hinged so that the two sections may be opened up to permit the placing of the feed or water within the pan or the 40 cleansing of the pan from time to time and prevent the entrance of rain.

Other objects will appear in the course of the following description.

45 My invention is illustrated in the accompanying drawings, wherein:—

Figure 1 is a perspective view of my improved feeder;

Figure 2 is a perspective view of the pan forming the base thereof and of the uprights 50 at the corners of the pan, the roof and guards being removed;

Referring to these drawings, 10 designates the pan proper which, as illustrated, is rectangular in plan view, and has an upwardly 55 extending rim 11. This pan is divided by vertical partitions into a T-shaped water

space 12, two spaces 13 designed to contain grit, and two relatively large spaces 14 designed to contain feed. It will be seen that the water spaces 12 extend all along one end of the feeder and that the opposite end contains a water space and the two grit spaces, while the grit spaces, the water spaces and the feed spaces are exposed along the side of the feeder.

At the corners of the pan there are provided the four upwardly extending supporting posts 15 which are preferably made of galvanized metal and angular in cross section. Mounted upon the upper ends of these 60 posts 15 are the upwardly convergent, roof supporting members 16 which are likewise angular in cross section or otherwise formed so as to secure a maximum of strength with a minimum of weight, these roof supporting 65 members 16 being connected by a transverse brace 17.

Connecting the upper ends of the posts 15 and extending along the sides of the structure are the strips 18, and hinged to 70 these strips are the roof sections 19, one of the sections 19 being so formed as to overlap the adjacent section 19 and form the ridge of the roof. These roof sections preferably extend outward beyond the hinge 18, 75 as at 20, and this outwardly extending portion of each roof section is deflected outward and upward or at an angle to the body of the roof section so that these sections 19 may be turned up beyond a vertical position 80 and supported in this position by the projecting portions 20.

The posts 15 at a suitable distance above the upper edge of the rim 14 are formed with vertically elongated slots 21, and supported upon these posts 15 immediately above the rim 14 are longitudinally extending, thin, metal strips 22 which are adjustably held to the posts by bolts 23 passing through the slots 21 and engaged by wing nuts 24. Thus these strips may be adjusted nearer to or further from the rim 14. Above these strips 23 are a plurality of strips 25 which may be permanently attached to the posts 15, these slats or straps being spaced a sufficient distance apart so as to permit light to enter and illuminate the pan, but the strips not being so far apart as to permit chickens to pass between the strips and into the pan.

It will be seen that the structure which I have devised is particularly effective for the

purpose of feeding poultry and particularly small chickens or the like. By adjusting the strips or slats 22 downward toward the rim, it is possible to prevent any but the 5 smallest chicks from having access to the water, feed and grit within the pan or to permit chickens of a larger growth to have such access without permitting full-grown chickens to have the feed therefrom. Furthermore, by adjusting the slats or strips 10 22 so as to permit the small chicks to insert their heads between the strip or slat and the rim but prevent the bodies of the chicks from passing, it is obvious that the 15 chicks cannot get into the pan, become drowned in the water, or contaminate the contents of the pan and waste the food. Of course, the food and the water is prevented from contamination by leaves or dirt 20 and the food from being soaked or rendered unfit by rain. By making the reservoir for water relatively large, which is accomplished by letting it extend the entire length of the pan and entirely across one end of the pan, 25 a supply of water sufficient for several days may be kept within the pan.

This construction has been found thoroughly effective in use and for the purpose intended. Obviously it may be modified in 30 minor details without departing from the spirit of the invention as defined in the appended claims.

It will be noted that there are four strips or slats 22 and by this means the feeder 35 may be used with different sized chickens. In other words, the feeder is to be placed at the juncture of a plurality of runs or yards, each yard or run containing a dif-

ferent sized chicken, and the slats on the four sides may be differently adjusted and 40 thus permit the chickens in the particular run for which the slat is adjusted to feed from the feeder.

I claim:—

1. A poultry feeder of the character described comprising a relatively shallow, rectangular pan having a rim, metallic posts angular in cross section attached to the corners of said rim and projecting upward therefrom, a roof supported on said posts, 50 slats connecting the upper ends of the posts, said posts just above the wall of the pan being vertically slotted, and slats disposed immediately above and in spaced relation to the rim of the pan, and bolts passing 55 through said slats and into said posts whereby the slats may be raised or lowered relative to the rim of the pan.

2. In a poultry feeder, a relatively shallow pan having an upwardly extending marginal rim divided to form a T-shaped water compartment extending the full length of the pan and having a width equal to the width of the pan, grit containing compartments disposed opposite to the cross bar of 65 the T-shaped compartment and at the opposite end of the pan, food compartments disposed between the grit compartments and the T-shaped end of the water compartment, and a superstructure disposed above the pan 70 in spaced relation to the upstanding rim of the pan.

In testimony whereof I hereunto affix my signature.

OVERTON M. BENNETT.
